G. A. LUTZ.
METHOD OF AND APPARATUS FOR ELECTROPLATING.
APPLICATION FILED JUNE 27, 1908.

Patented Nov. 3, 1908.

UNITED STATES PATENT OFFICE.

GEORGE A. LUTZ, OF PLAINFIELD, NEW JERSEY, ASSIGNOR TO AMERICAN CIRCULAR LOOM COMPANY, OF PORTLAND, MAINE, A CORPORATION OF MAINE.

METHOD OF AND APPARATUS FOR ELECTROPLATING.

No. 902,892.

Specification of Letters Patent.

Patented Nov. 3, 1908.

Application filed June 27, 1908. Serial No. 440,774.

To all whom it may concern:

Be it known that I, GEORGE A. LUTZ, a citizen of the United States, and resident of Plainfield, in the county of Union and State 5 of New Jersey, have invented certain new and useful Improvements in Methods of and Apparatus for Electroplating, of which the following is a specification.

In simultaneously electro plating the interior and exterior of hollow articles, such as pipes and the like, if the electric current is allowed to flow continuously through the anode within such article during the whole length of time that the current flows through 10 the anode or anodes exterior to such article, a thicker plating will be deposited upon the interior of the article than upon its exterior, and where such thicker inner plating is not required there is considerable loss occasioned by such extra plating on the interior 15 of the article.

The object of my invention is to simultaneously plate the exterior and the interior of hollow articles, such as pipes, and to regulate or control the plating of the interior of the hollow article to the end that such plating may be approximately of the same thickness as the plating on the exterior of the article.

In carrying out my invention I support a hollow article within an electrolytic bath, with one or more anodes within such article and one or more anodes in the bath without such article, the inner and outer anodes being connected with one side of an electric circuit, and the article to be plated connected with the other side of said circuit, and I cause the electric current to flow simultaneously through said inner and outer anodes 20 for a desired period of time, substantially sufficient to provide the required plating upon the interior of the article, and then I cut off the flow of current through the inner anode or anodes while permitting the current to continue to flow for a further desired period of time through the outer anode or anodes, all whereby the inner and outer surfaces of the hollow article may be plated respectively for any desired thickness of plating. The cutting off the current from the inner anode or anodes is effected without stopping the flow of current through the outer anode or anodes, enabling the electro plating of the article to be continuously car-

ried on both within and without the same 55 without interruption, until the inner and outer surfaces are plated as desired, all whereby economy is effected in time and operation in handling the articles, and saving electro plating material and power, producing an improved article for the purpose 60 intended.

In the accompanying drawings I have illustrated an apparatus by means of which my improved method of electro plating 65 may be carried out, and wherein the flow of the current through the anode or anodes within the article to be plated may be automatically regulated in accordance with the time desired for the flow of the current, although such flow may be controlled by hand 70 operation or in any other suitable manner.

In said drawings Figure 1 is a partly sectional and partly diagrammatic view illustrating means for carrying out my invention, and Fig. 2 is a top view of the electro plating tank with the cathode plate removed.

The hollow article 1 to be plated, such as a pipe, is placed within a suitable tank 2 adapted to contain an electrolytic bath, and at 3 is indicated a cathode plate from which pipe 1 depends into the bath, the pipe being shown detachably connected with said plate by means of screw threads. Within pipe or article 1 is placed one or more anodes 4 of suitable electro-plating metal, which anode is shown as suspended from cathode plate 3 and insulated therefrom by suitable insulation 5. At 6 are one or more anodes within tank 2 located exterior to pipe 1 and shown suspended by hooks 7 from a conductor ring 8 supported within the tank, as by brackets 9. Ring 8 and thereby anodes 6 are connected with one terminal of a suitable generator 10, as by conductor 11, the other terminal of which generator is connected by conductor 12 with cathode plate 3; the inner anode or anodes 4 are connected by a suitable conductor 13 with conductor 11, or with the corresponding terminal of the generator, whereby the inner and outer anodes may be simultaneously included in the circuit of the generator. To control the circuit of the inner anode or anodes 4 without disturbing the circuit of the outer anode or anodes 6, a suitable switch 14 is shown included in the circuit 13, whereby said circuit may be open to cut out anode or anodes 4 while the cur-

rent continues to flow through anodes 6. Where it is desired to automatically control the circuit of the inner anode or anodes such circuit may be provided with a clock-controlled make and break device which will close such circuit and then open the same automatically as desired. For this purpose I have shown conductor 13 as divided and provided with spring contacts 13^a, 13^b, the latter contact bearing continuously against a metal disk 15 controlled or supported by the hour-hand arbor or sleeve of a suitable clock 16, the disk 15 being adapted to make and break circuit with contact 13^a. For this purpose I have shown the periphery of disk 15 provided with insulating pieces 15^a arranged at suitable distances apart, whereby as disk 15 revolves and the insulating pieces 15^a engage contact 13^a the circuit of the inner anode 4 will be broken and when contact 13^a engages disk 15 said circuit will be closed. The spacing of insulating pieces 15^a with respect to the intermediate metal portions 15^b of disk 15 may be proportioned as desired according to periods of time, as for instance, each 5 minutes the circuit may be broken and closed for any given period, say each 2½ minutes, whereby for the period of 5 minutes current will flow through the outer anodes continuously while during such time the current will flow through the inner anode or anodes for only a portion of such period.

My improved method of electroplating may be carried out as follows: The article to be plated being placed in the bath and the circuits of the generator closed current will flow through both the inner and outer anodes simultaneously, causing the electro deposit of the material upon the interior and exterior of the pipe or other article simultaneously, and when the interior surface of such article has been plated sufficiently the circuit of the inner anode or anodes will be broken, as by hand operation of switch 14, or by the clock controlled contacts, and the current will continue to flow through the outer anodes for a further period of time without requiring pipe 1 to be moved, and when the exterior of the pipe is sufficiently plated it may be removed from the tank and another pipe inserted, and so on.

Instead of starting to plate the article with the current flowing through both the outer and inner anodes simultaneously, and then cutting out the inner anode, the current may be caused to flow first through the outer anode or anodes for a desired length of time, and then the current may be caused to flow through the inner anode or anodes while still continuing to flow through the outer anode or anodes until the desired thickness of plating on the interior and exterior of the article is accomplished, or the plating may be started by first passing the current

through the outer anode or anodes, then after a period cutting into the circuit the inner anode or anodes, and then after a period cutting out the inner anode or anodes and permitting the current to flow through the outer anode or anodes for a further period. In either of the above named ways the current is caused to flow simultaneously through the inner and outer anodes with a longer period of flow of the current through the outer anode or anodes than through the inner anode or anodes. By the method described the amount of plating on the interior and exterior of hollow articles may be readily determined and proportioned, so that substantially approximately the same thickness of plating may be placed upon the interior and exterior of the article, or the interior or exterior may be thicker than the exterior or interior, respectively, as required, according to the period of time that the current flows through the inner or outer anodes, the plating operation being continuous and regular, with economy in time, labor and cost of material and the production of improved electro-plating.

While I have shown provision for plating a single article, such as pipe 1, it will be understood that several of such articles or pipes may be plated simultaneously in the same bath by suitably arranged circuits in manner obvious to those skilled in the art.

Having now described my invention what I claim is:—

1. The method of electro-plating the interior and exterior of a hollow article consisting in simultaneously passing electric current through anodes within and without such article and causing the current to flow for a longer period of time through one of the anodes than through the other anode.

2. The method of electro-plating the interior and exterior of a hollow article consisting in simultaneously plating the interior and exterior surfaces thereof for a period of time and plating the outer surface for a longer period of time than the inner surface.

3. The method of electro-plating the interior and exterior of a hollow article consisting in simultaneously plating the interior and exterior surfaces thereof for a period of time, and causing more current to flow through one of the anodes than the other.

4. The method of electro-plating the interior and exterior of a hollow article consisting in simultaneously passing electric current through anodes within and without such article, and causing more current to flow through the outer anode than through the inner anode.

5. The method of electro-plating the interior and exterior of a hollow article consisting in simultaneously passing electric current through anodes within and without the article, and then cutting off the current

from the inner anode and causing the current to continue to flow through the outer anode for a desired period of time.

6. An electro-plating apparatus comprising a tank, means to support a hollow article therein, means to simultaneously support anodes within and without said article, a generator having one side of the circuit connected with the inner and outer anodes, and 10 means in the circuit of the inner anode for automatically breaking said circuit independently of the circuit of the outer anode.

7. An electro-plating apparatus comprising a tank, means to support a hollow article therein, means to simultaneously support 15

anodes within and without said article, a generator having one side of the circuit connected with the inner and outer anodes, and a clock-controlled make and break mechanism in the circuit of the inner anode to automatically make and break said circuit independently of the circuit of the outer anode. 20

Signed at New York city, in the county of New York, and State of New York, this 25th day of June, A. D. 1908.
